[57] CLAIM

The ornamental design for a belt attachment for articles having a belt clip, as shown and described.

DESCRIPTION

FIG. 1 is an isometric view of a belt attachment for articles having a belt clip showing my new design from the front side in an unfolded condition;

FIG 2 is an isometric view thereof shown from the rear side in the unfolded condition;

FIG. 3 is an isometric view thereof shown from the front in a folded condition;

FIG. 4 is an isometric view thereof shown from the rear in the folded condition; and,

FIG. 5 is a top plan view thereof shown in the folded condition.
